UNITED STATES PATENT OFFICE.

ISAAC GILBERT, OF CHICAGO, ILLINOIS.

LIFE-SAVING APPLIANCE.

1,180,839.

Specification of Letters Patent. Patented Apr. 25, 1916.

Application filed September 20, 1915. Serial No. 51,605.

To all whom it may concern:

Be it known that I, ISAAC GILBERT, a citizen of the United States, and a resident of the city of Chicago, county of Cook, and 5 State of Illinois, have invented certain new and useful Improvements in Life-Saving Appliances, of which the following is a specification.

My invention relates to improvements in 10 life saving appliances, and has for its object, the provision of an improved construction of this character arranged and designed to preserve human life in case of marine disasters.

15 The invention consists in the combinations and arrangements of parts hereinafter described and claimed.

The invention will be best understood by reference to the accompanying drawings 20 forming a part of this specification, and in which,

Figure 1 is a vertical section of a buoyant suit embodying my invention, inner portions thereof being shown in elevation, Fig. 25 2, a view illustrating the form of hand cover employed in the suit, Fig. 3, a section taken on line 3—3 of Fig. 1, Fig. 4, a vertical section taken at right angles to Fig. 1, Fig. 5, a horizontal section taken through 30 the body portion of the suit, and Fig. 6, an enlarged vertical section taken through a head piece employed in the suit.

The preferred form of construction, as 35 illustrated in the drawings, comprises an outer waterproof garment member 7 shaped to fit the human form and preferably made of cloth treated with rubber to render the same absolutely water-tight. The garment is provided at its top with an opening sufficiently 40 large to permit of the same being put on the human form and the edges of this opening are provided with a draw string 8 by means of which the same may be drawn about a buoyant head piece 9 preferably 45 formed of cork and provided on its exterior surface with an annular groove 10 for the reception of said draw string, as indicated. A rubber ring 11 is secured at one side to the suit 7 in position to pass over the head piece 50 9 and serve as a means for further sealing the juncture with the suit 7. As best shown in Fig. 6, the head piece 9 is made concave on its under side to fit over the head of the wearer in substantially cap-form and head 55 pads 12 and 13 in the form of annular rings of rubber hose or the like are positioned in

said recess to rest upon the head, said rings being provided with notches 14 in their upper sides to permit of the free circulation of air through said recess. A central perforation 15 leads upwardly from said recess through the head piece and an upstanding flexible tube or pipe 16 leads from said perforation. The tube 16 is provided at its upper end with a spring held valve or cover 60 17 which is normally held in open position and a spring catch 18 is provided at one side to engage said valve and hold the same in closing position. Catch 18 is connected by means of a cord 19 with a lever 20 by means 65 of which the valve 17 may be released and air freely admitted to the interior of the suit through the tube 16. By this arrangement, it will be observed that when the suit is floating in the water in upright position, the 70 tube 16 will normally project above the waves on the water, thus permitting of the free entry of air to the interior of the suit and excluding the water. In case the occupant of the suit is compelled to jump from 75 an elevation into the water or for other reason is compelled to be temporarily submerged, the valve 17 may be closed during such submergence and then readily opened when the occupant returns to the surface of 80 the water.

The head piece 9 is provided with branch perforations 21 leading from the central perforation 15 and a flexible ear piece 22 has its ends secured in said branch perforations 90 and is arranged to pass over the ears and under the chin of the wearer, said ear piece being provided on its inner side with ear muffs 23 for encompassing and protecting the ears of the wearer against cold. Air 95 passages 24 are also provided on ear pieces 22 in open communication with branch passages 21, said passages 24 being provided with mouth openings 25 adjacent the mouth of the wearer in position to permit of free 100 circulation of air thereto, said ear pieces and passages being formed of slightly stiff rubber or similar material having sufficient flexibility to permit of the same being readily placed in position under the chin of the 105 wearer and sufficient stiffness to maintain the passages 24 open for the free circulation of air. Whistle tubes 26 are arranged in the passages 24 and protrude through the mouth openings 25 in operative relation 110 with the mouth of the wearer, said whistle tubes leading to a central whistle tube 27

located in the tube 16 and communicating at its upper end with a whistle 28 by means of which signals may be given by the wearer.

The upper leg and lower waist portions of 5 the suit 7 are provided with buoyant padding 29 inclosed by a waterproof casing 30 as shown, said padding being comparatively light around the leg portions but materially heavier around the waist portions, as indicated.

A buoyant inner garment 31 which is substantially in the form of a vest openable at the front and provided with suitable fastenings 32, is arranged within the outer garment 15 7 and is adapted to be fitted around the torso of the wearer after the lower portion of garment 7 has been put on but before the upper portion has been placed in operative position. The garment 31 is provided 20 with buoyant padding 33 around the body portion and padding 34 around the lower arm portions, the arm portions thereof being provided with gloves 35 fitting the hand portions 36 of the outer garment 7 which are 25 also in the form of gloves. The hand portions 36 of the outer garment 7 are provided on their backs with webs 37 extending between the fingers to assist the occupant in swimming or propelling himself through 30 the water.

A double pocket 38 is provided at one side of the garment 31 for the reception of an electric flash light and a water bottle, and another pocket 39 is arranged at the other 85 side of the garment 31 for the reception of bread for the use of the occupant.

The leg and waist portions of the outer suit 7 are provided with a heavy lining 40 or inner suit of wool or other non-heat conducting material to preserve the warmth of 40 the occupant. Reinforcing bands or belts 41, 42 and 43 are placed respectively around the waist, chest and neck portions of the outer suit and a looped rope 44 is secured 45 to the band 41 to facilitate rescue of the occupant. Glass covered eye-openings 45 are arranged in the suit 7 opposite the eyes of the occupant to permit of observation.

While I have illustrated and described the 50 preferred form of construction for carrying my invention into effect, this is capable of variation and modification without departing from the spirit of the invention. I, therefore, do not wish to be limited to the 55 precise details of construction set forth, but desire to avail myself of such variations and modifications as come within the scope of the appended claims.

Having described my invention what I 60 claim as new and desire to secure by Letters Patent is:

1. A buoyant suit comprising an outer flexible waterproof garment open at the top, the leg and waist portions of said suit being 65 padded with buoyant material; an inner

buoyant garment arranged to fit about the human torso; and means for sealing the opening in said outer suit, substantially as described.

2. A buoyant suit comprising an outer 70 flexible waterproof garment open at the top; a head piece provided with means for admitting air; an inner buoyant garment arranged to fit about the human torso; and means for sealing the opening in said outer 75 suit, substantially as described.

3. A buoyant suit comprising an outer flexible waterproof garment open at the top, the leg and waist portions of said suit being padded with buoyant material; a head 80 piece provided with means for admitting air; an inner buoyant garment arranged to fit about the human torso; and means for sealing the opening in said outer suit, substantially as described.

4. A buoyant suit comprising an outer flexible waterproof garment open at the top, said opening being provided with draw strings; a head piece provided with means for admitting air and an annular groove on 90 its outer side to receive the edges of the opening in said outer garment, there being a central perforation extending through said head piece; a resilient ring secured to said outer suit adjacent the opening therein and 95 adapted to encompass said head piece and seal said outer suit thereagainst; an up-standing flexible tube communicating with the opening in said head piece; a sealing valve for said tube; flexible ear pieces secured to said head piece and arranged to cover the ears and pass under the chin of the wearer, said ear pieces being provided with air passages communicating with the perforation through said head piece; and means 100 for rendering said suit buoyant, substantially as described.

5. A buoyant suit comprising an outer

flexible waterproof garment open at the top, said opening being provided with draw 110 strings; a head piece provided with means

for admitting air and an annular groove on its outer side to receive the edges of the opening in said outer garment, there being a central perforation extending through said 115 head piece; a resilient ring secured to said outer suit adjacent the opening therein and

adapted to encompass said head piece and seal said outer suit thereagainst; an up-standing flexible tube communicating with the opening in said head piece; a sealing 120 valve for said tube; flexible ear pieces secured to said head piece and arranged to

cover the ears and pass under the chin of the wearer, said ear pieces being provided 125 with air passages communicating with the perforation through said head piece; buoyant padding about the upper leg and waist portions of said outer suit; an inner garment in the form of a vest openable at the 130

front and provided about the body and lower arm portions with buoyant padding; reinforcing bands about the waist, chest and neck portions of said outer suit; and a rope secured in loops about the waist band, substantially as described.

In testimony whereof I have signed my

name to this specification in the presence of two subscribing witnesses.

ISAAC GILBERT.
